UNITED STATES PATENT OFFICE.

JOHN M. VAN FLEET, OF KENTON, OHIO.

APPARATUS FOR REMOVING STAMPED METAL ARTICLES FROM DIES.

SPECIFICATION forming part of Letters Patent No. 532,484, dated January 8, 1895.

Application filed November 16, 1893. Serial No. 491,121. (No model.)

To all whom it may concern:

Be it known that I, JOHN M. VAN FLEET, a citizen of the United States, residing at Kenton, in the county of Hardin and State of Ohio, have invented a certain new and useful Improvement in Apparatus for Removing Stamped Metal Articles from Male Dies, of which the following is a specification, reference being had therein to the accompanying drawings.

My invention relates to an apparatus for removing stamped metal articles from male dies.

It is well known that in stamping metal cylinders and other like articles great difficulty is often encountered in removing the articles from the male die, owing to the tenacity with which the shaped metal adheres to the die, this being especially true where an attempt is made to stamp up a cylinder of any considerable length.

The object of my invention is to provide means whereby, when the male die, with the stamped article clinging to it, is raised out of the female die, heat may be applied to the entire outer surface of the shaped metal, so as to expand and loosen the article on the die.

With this object in view, my invention consists in the novel construction and arrangement of parts hereinafter described and claimed.

Figure 1 of the drawings is a vertical sectional view showing a stamped article on a male die or plunger, and also my apparatus for applying heat to said article to expand it so that it can be readily removed from the die. Fig. 2 is a top plan view of my apparatus for applying heat to the stamped article. Fig. 3 is a vertical elevation of the same.

Referring to the drawings, D represents a hollow cylinder made of any suitable material, and formed in sections, hinged together, as at 3. The upper end of this cylinder is partly covered, the diameter of the central opening j being but slightly greater than the diameter of the male die or plunger. In this cylinder are a number of perforations 5, in which are inserted inlet-pipes 6, which communicate, through branch-pipes 7, with a main pipe 8, the latter being connected to a suitable gas-supply D'. The main pipe and branch pipes are made of flexible material, in order to facilitate the placing in position and removal of the cylinder D, the latter being provided with handles F. Openings 9

formed in convenient places in the cylinder serve to admit drafts of air.

E represents a male die or plunger.

G represents a stamped article on the die.

In operation the cylinder D is placed around the suspended die and the stamped article thereon, when the upper end of the cylinder will rest on the upper edge of the article, as seen at 4. Gas being then admitted to the cylinder through the various pipes and lighted, the heat developed, acting directly on the stamped article, will cause expansion of the latter, when the apparatus, which, as before stated, is suspended from the upper edge of the stamped article, will by gravity gradually force the article off from the die. By this means all danger of cracking or breaking the stamped article in the act of removing it is obviated.

Having thus described my invention, what I claim as new, and desire to secure by Letters Patent, is—

1. An apparatus for removing stamped metal articles from male dies, consisting of a perforated cylinder adapted to encompass the stamped article on the die and to be suspended from its top edge, a gas-supply, a main pipe connected therewith, branch pipes connected with the main pipe, and inlet-pipes leading from the branch pipes into the cylinder through the perforations in the latter, whereby when the gas is ignited and the article expanded by the applied heat the downward pressure exerted by the weight of the apparatus will cause the removal of the article from the die.

2. An apparatus for removing stamped metal articles from male dies, consisting of a perforated cylinder in two parts, hinged together, adapted to encompass the stamped article on the die and to be suspended from its top edge, a gas-supply, a main pipe connected therewith, branch pipes connected with the main pipe, and inlet pipes leading from the branch pipes into the cylinder through the perforations in the latter, substantially as described and for the purposes set forth.

In testimony whereof I affix my signature in presence of two witnesses.

JOHN M. VAN FLEET.
